(57) **CLAIM**

The ornamental design for the computer keyboard, as shown and described.

DESCRIPTION

FIGS. 1 and 2 are perspective views showing the computer keyboard according to my new design;

FIG. 3 a side elevation view thereof;

FIG. 4 is a front elevation view thereof;

FIG. 5 is an opposite side elevation view thereof;

FIG. 6 is a rear elevation view thereof; and,

FIG. 7 is a top view thereof.

Broken lines shown in the drawings illustrate portions of the computer keyboard, and form no part of the claimed design.
